UNITED STATES PATENT OFFICE.

JOSEPH R. McCARGAR, OF GRAND RAPIDS, MICHIGAN, ASSIGNOR TO STOW & DAVIS FURNITURE COMPANY, OF GRAND RAPIDS, MICHIGAN, A CORPORATION OF MICHIGAN.

DESIGN FOR A DESK.

Application filed November 1, 1923. Serial No. 7,644. Term of patent 3½ years.

To all whom it may concern:

Be it known that I, JOSEPH R. McCARGAR, a citizen of the United States, residing at the city of Grand Rapids, in the county of Kent and State of Michigan, have invented a new, original, and ornamental Design for Desks, of which the following is a specification, reference being had to the accompanying drawing, forming a part thereof.

In the drawing,

The figure is a perspective view of a desk, showing my new design.

I claim:

The ornamental design for a desk, substantially as shown.

JOSEPH R. McCARGAR.
